UNITED STATES PATENT OFFICE

164,629

BRACELET OR SIMILAR ARTICLE

Jerry Fels, Los Angeles, Calif.

Application March 27, 1950, Serial No. 8,792

Term of patent 7 years

(Cl. D45—4)

To all whom it may concern:

Be it known that I, Jerry Fels, a citizen of the United States of America, and a resident of the city of Los Angeles, in the county of Los Angeles, and in the State of California, have invented a new, original, and ornamental Design for a Bracelet or Similar Article, of which the following is a specification, reference being had to the accompanying drawing, which drawing forms a part of this invention.

Figure 1 is a plan view of a bracelet or similar article, showing my new design.

Fig. 2 is a side elevational view thereof, a portion of one of the links being broken away for purposes of illustration only.

Fig. 3 is a cross-sectional view of one of the links taken on the line 3—3 of Fig. 2, illustrating the hollow center, the open top and the top surface configuration of the links.

The dominant features of my design reside in the links shown in full lines, these links being repeated as indicated by the broken lines.

I claim:

The ornamental design for a bracelet or similar article, substantially as shown and described.

JERRY FELS.
